UNITED STATES PATENT OFFICE

1,973,909

COKE AND GAS MANUFACTURE

Gerald J. Nordmeyer, Nutley, N. J., assignor to
The Koppers Company of Delaware, a corpora-
tion of Delaware

Application September 24, 1931, Serial No. 564,799

4 Claims. (Cl. 202—23)

My invention relates to the operation of coke ovens. It relates especially to the manufacture of gas from oils, such as heavy petroleum oils, in coke ovens.

5 Batteries of by-product coke ovens are generally operated primarily for the production of two products—coke and gas. The market for these products usually varies with the seasons, and the relative demand for coke and gas is also 10 subject to seasonal fluctuation. Coke produced during the slack season is readily stored until there is a better market for it, but gas must generally be produced at a rate substantially corresponding to the current demand.

15 Flexibility with regard to the amount of gas produced is therefore a highly desirable feature of coke oven installations, and various means of achieving this flexibility have been devised. For example, during the season when the demand for 20 gas is small, part of the gas produced by the battery may be employed for underfiring, and when the demand increases, producer gas or water gas is employed for underfiring, releasing all of the coke-oven gas for sale. The supply of sur- 25 plus gas can be further augmented by manufacturing water gas from the coke produced.

Such expedients require considerable equipment in addition to the coke-oven battery, in the form of gas producers or water-gas sets, and 30 since this equipment is not usually in continuous operation its maintenance and occasional operation add appreciably to the cost of the gas produced.

To eliminate this expense and to increase the 35 flexibility of the coke-oven operation, various attempts have been made in the past to employ coke ovens for carbonizing hydrocarbon oils such as pitch and certain petroleum fractions capable of producing large quantities of gas per unit of 40 space required.

The gasification or distillation of heavy hydrocarbon oils, such as the so-called "bunker oil", in coke ovens, has been rather carefully studied. It has been found that a typical coke oven, such 45 as one of the type described in the Becker Patent No. 1,374,546, with a coking capacity of 20 tons of coal per day, can convert 5,000 gallons of bunker oil or the like into gas and coke per day.

Each ton of coal produces about 11,000 cubic 50 feet of 550 B. t. u. gas, and when coal gas is employed for underfiring, about 40% of this amount is required, leaving 6,600 cubic feet of surplus gas per ton of coal. The equivalent amount of oil, 250 gallons, produces about 20,000 cubic feet 55 of 1250 B. t. u. gas, and if this is diluted to 500

B. t. u. per cubic foot, the gas production is 44,500 cubic feet.

This makes the ratio of maximum to minimum gas production about 7 to 1, and the amount of gas produced by a battery of coke ovens can be 60 varied as desired within this ratio by gasifying oil in part of the ovens, and coal in the others.

Since the amount of gas produced by any given battery of coke ovens can be varied over a range which is greater than the usual difference between 65 the minimum daily load and the maximum daily load on a gas plant or gas distributing system, it seems that gasification of oil in coke-oven batteries should be a solution of the problem of providing sufficient flexibility for gas plant pur- 70 poses. However, technical difficulties have been encountered which have in the past prevented the general adoption of this practice. For example, it has been difficult to obtain a good grade 75 of coke, tar production has been high, and the yield and quality of oil gas have frequently fallen below the results theoretically obtainable, and actually obtainable under optimum conditions.

An object of my present invention is to provide 80 a method of gasifying heavy hydrocarbon oils, such as bunker oil, in by-product coke ovens, whereby the difficulties previously encountered in converting such oils into coke and gas are overcome.

A second object of my invention is to provide 85 a method of operating coke ovens which is more flexible with respect to the quantity of gas produced than methods previously employed.

Another object of my invention is to provide 90 an improved method of producing oil gas in coke ovens, and suitable apparatus therefor.

My invention has for further objects such other operative advantages and results as are found to obtain in the process and apparatus described and claimed herewith.

The nature of my invention is such that existing coke-oven installations of any usual type, such as the Becker oven described in the patent referred to hereinabove, for example, can readily be adapted to its practice. My invention contem- 95 plates introducing oil into the lower portion of a coking chamber by means of oil spray lines or the like, which may be inserted through the charging holes in the oven top. These sprays and pipes are preferably fabricated from tempera- 100 ture-resistant metal, and extend about half or two thirds of the distance from the top to the bottom of the oven. They may terminate about three to five feet from the bottom of the oven, for 105 example.

By this means, coking or carbonization of the oil residue is caused to take place chiefly in the lower part of the oven chamber, and the free space in the upper part of the oven allows "fixing" of the oil gas before its discharge from the coking chamber. The yield and quality of the gas may be further improved if an atmosphere of steam or blue water gas is maintained in the oven, as the oil gas is thus fixed more effectively.

10 I will now describe the details of my invention with reference to the accompanying drawings, in which Figure 1 is a vertical sectional view of a coke oven adapted to the practice of my improved method of coke-oven operation and oil gasification.

15 Fig. 2 is a vertical sectional view transverse-
ly of Figure 1.

A coke-oven battery consists of any desired number of ovens, such as the oven generally indicated by the numeral 2 in the drawing. Each oven is provided with a suitable number of charging ports or openings 3, three of which are shown in the present instance. The ovens are heated to the desired temperature in a known manner by suitably arranged flues in the walls surrounding the coking chamber.

20 An offtake 5 and ascension pipe 6 conduct gases from each oven to a collecting main 7. In some instances when coal is coked in part of the ovens of a battery and oil in others, and under other circumstances, it may be preferable to employ two collecting mains, which may both be connected to the ascension pipes 6, or which may be at opposite ends of the ovens, each of which is then provided with two ascension pipes. Removable doors 9 and 10 are provided at the ends of each oven.

25 Any desired number of the ovens 2 constituting the battery may be employed to convert oil into gas and coke in accordance with my present invention. Oil such as bunker oil is supplied to these ovens, which are preferably consecutive ovens if the whole battery is not so employed, by means of a supply pipe and header (not shown) connected to branch pipes 12 which extend along the top of that portion of the battery in which oil is to be coked.

30 Each of the branch pipes 12 is connected with a series of pipes 14, which are usually smaller than the pipes 12, and which correspond in number to the number of ovens in which oil is to be coked. These pipes 14 extend through discs or other suitable closing means 15 in the charging ports 3 of the ovens to which oil is delivered.

35 Each pipe 14 contains a valve 17 or other suitable means for controlling the flow of oil there-
through, and each terminates in a spray nozzle 18, or other suitable distributing means, which is preferably about three to five feet from the bottom or sole of the oven, as previously stated.

40 Oil is delivered into the heated oven either continuously or intermittently at a rate corresponding to the size of the oven and the temperature maintained therein. In an oven of the usual size, this rate might be about 25 gallons per minute when the temperature of the oven is about 1450 to 1500° F.

45 The oil is heated before its discharge from the sprays 18 by passing through pipes 14. It may also be preheated to any desired extent by means of steam coils in the oil storage tank, or by circulating it through the flushing main or collect-
ing main 7 before delivering it to the pipes 12, in the manner described in the copending appli-

cation of C. J. Ramsburg, Serial No. 555,228, filed August 5, 1931.

50 Whether the oil is supplied continuously at a rate corresponding to the rate at which the residue is coked, or intermittently at a higher rate with the flow periodically interrupted to allow volatile material to vaporize and the residue to carbonize, oil coke is formed and builds up in the bottom of the oven chamber, and oil vapor and gas are given off in large quantities.

55 When the deposit of coke has reached a sufficient depth, such as a depth approximating but preferably somewhat less than the distance between the sprays 18 and the bottom of the oven, the supply of oil is temporarily discontinued, and the coke is pushed out in the usual manner through the doors 9 and 10.

60 The oil gas and vapor is cracked or fixed in the free space above the sprays 18 in the oven chamber, from which it then passes through the ascension pipe 6 to the collecting main 7. This provision of a cracking or fixing space or chamber within the coke oven and out of contact with the oil spray greatly improves the quality of gas evolved, and delivering the oil to the lower part 100 of the oven makes this possible and substantially limits coke formation to the lower part of the oven.

65 Still more favorable results are obtained if an atmosphere of steam and/or blue water gas is maintained in the parts of the oven chamber where most of the cracking occurs. I have found that this may be readily accomplished by injecting steam into the lower part of the oven, as through passages 21 which may terminate in 110 sprays or nozzles 22.

70 These nozzles may conveniently be mounted on the coke-oven doors 9 and 10, respectively, through which the passages 21 penetrate, as shown. They are supplied with steam from 115 steam pipes 24 and 25, to which they are connected by flexible hoses 26, and readily detachable coupling members 27. The flow of steam through these nozzles is controlled by valves 28 or other suitable means. The passages 21 are preferably 120 inclined downwardly so that steam is discharged toward the bottom of the chamber, where coke is first deposited.

75 As an alternative, steam may be supplied to the chamber through a suitable duct and ports opening upward into the chamber. In either case, the steam reacts with coke deposited in the lower part of the oven to form blue water gas, thereby increasing the yield of gas and improving its quality, as well as reducing the amount of coke formed 130 and making it unnecessary to push coke as frequently.

80 The steam is preferably admitted at such a rate that it is substantially completely decomposed before passing from the oven, at least in the later 135 stages of the operation.

85 It will be obvious to those skilled in the art that certain modifications are possible in the process, apparatus, and materials described hereinabove without departing from the spirit of my invention, and it is my intention to cover in the claims such modifications as are included within the scope thereof.

90 I claim as my invention:

95 1. The method of manufacturing coke and gas 140 from oil in a retort oven comprising, introducing oil through pipes extending to a short distance above the bottom of the retort and spraying the oil on the bottom thereof while the retort is being heated and gradually accumulating the oil in a 15

- pile only part way up the retort and simultaneously coking it on said bottom, maintaining an upper gas-fixing space free from entering oil and above the accumulating pile of oil in the lower part of the retort, externally heating the side portions of both the coking oil pile and the upper gas-fixing space in the retort to superheat the major portion of the gas-fixing space which is opposite to and externally heated by said heating and thereby effecting the coking of the so introduced oil in the lower part of the retort and superheating the upper gas fixing space in the retort, withdrawing oil gas thereby vaporized and distilled off from the retort through said gas-fixing space while it is superheated as aforesaid and free from entering oil and accumulated coking oil and thereby fixing said oil gas as it flows off from the retort through said gas-fixing space, and withdrawing finished coke from the retort.
2. A method as claimed in claim 1, and which includes the steps of introducing steam into the coked oil to produce water gas therefrom and withdrawing the water gas off through the retort simultaneously with the vaporized and distilled oil gas withdrawn as aforesaid.
3. A method as claimed in claim 1, and which includes the step of introducing steam into said retort to produce an atmosphere of steam in the gas-fixing gas-space to favor the fixing of the oil gas therein.
4. A method as claimed in claim 1, and which includes the steps of introducing steam into the coked oil to produce water gas and at a rate corresponding to the rate at which the steam is decomposed by reaction with the coke produced as aforesaid, and withdrawing the water gas so produced off through the retort simultaneously with vaporized and distilled oil gas withdrawn as aforesaid.
